UNITED STATES PATENT OFFICE.

ROY G. SAVILLE, OF MOUNTAIN PARK, OKLAHOMA.

CALF WEANER.

Application filed March 1, 1927. Serial No. 171,829.

This invention relates to calf weaners and the general object of the invention is to provide a weaner which when applied to a calf will absolutely prevent the calf from sucking, which is very simple in construction, and may be easily applied.

My invention is illustrated in the accompanying drawings wherein:—

Figure 1 is a front elevation of a calf weaner constructed in accordance with my invention;

Figure 2 is a fragmentary vertical sectional view thereof;

Figure 3 is a perspective view of one of the nostril-engaging members.

Referring to these drawings it will be seen that the weaner is constructed from a sheet of metal 10, bent so that the upper portion of the sheet is transversely curved to fit over the face of the calf and having two openings 11 and 12 at about the middle of the sheet. The lower end of the sheet is extended upward in a curve from about the point 13, as at 14, so as to provide a slightly curved, outwardly extending flange 15. Rearward of this flange the corners of the sheet are outwardly bent so as to provide obtusely angled, outwardly projecting portions 15^a on each side of the shield 10.

Riveted or otherwise attached to the outer face of the sheet is a downwardly extending bar 16 whose end is angularly bent and extended through the opening 12. Disposed parallel to the bar 16 is the bar 17 which is pivoted upon a rivet 18 at its upper end, the lower end of the bar being angularly bent and extended through the slot 11. These angularly bent ends are designated 16^a and 17^a respectively and are designed to be inserted in the nostrils, these angularly bent portions 16^a and 17^a being preferably bent inward or towards each other and slightly upward, as shown in Figure 3. The interior of the shield 10 on the concavo-convex portion thereof, is lined with leather 19. Just above the slot 11, the leather lining and the shield are perforated for the passage of an adjusting pin 20 which extends through an opening in the bar 17. This permits the lower end of the bar 17 to be adjusted toward or from the lower end of the bar 16 to thus fit the calf's nostrils.

For the purpose of holding the shield in place, the leather lining 19 is extended to form two bands or straps 21 and 22, one of these bands having a buckle and the other

having perforations coacting therewith. These bands constitute a head stall. Passing through the slots 23 in the shield and lining are the looped ends of straps 24, one of these straps carrying a buckle and the other strap coacting therewith. These straps also constitute part of the head stall and are designed to pass beneath the head of the animal and around its throat. In putting this weaner in place, the pin 20 is removed and the bar 17 shifted laterally, the shield is then applied and the bar 17 again shifted laterally in a reverse direction to carry the hook 17^a into the calf's nostril, the other hook 16^a having been previously inserted. This bar is again fastened in place by the pin 20 and thus it is impossible for the calf to shift the device sidewise and thus get it out of position. Obviously it is impossible for the calf to suck the cow with this device over its face.

The pin 20 is held in place in its engaged position in any suitable manner but I have shown for this purpose a spring 25 which carries this pin and urges it inward. I do not wish to be limited to this means, however.

The shield which constitutes this calf weaner fits over the top of the nose and extends upward to about two inches of the eyes. It does not, however, cover the eyes nor interfere with sight as the two hooks engaging the nostrils hold the shield in place, the lower edge of shield being about two inches below the muzzle of the animal. The straps 21 and 22 go around the neck while the straps 24 go under the jaws. This weaner in use keeps the cow's nipples out of reach of the mouth of the calf, but does not gouge or otherwise injure the udder. The hooks hold the weaner down and prevent the calf from turning his head to one side and sucking which they do with other weaners. Weaners constructed in accordance with this invention have been found to be very effective and thoroughly satisfactory.

I claim:—

1. A calf weaner comprising a metallic shield having its upper portion transversely curved to fit over the face of a calf and having a head stall whereby it may be held in place, the lower portion of the shield being bent downward and then upward and the lateral corners of the shield being bent outward, and means on the shield for engaging the calf's nostrils.

2. A calf weaner comprising a metallic shield having its upper portion transversely curved to fit over the face of a calf and having a head stall whereby it may be held in place, the lower portion of the shield being bent downward and then upward and the lateral corners of the shield being bent downward, and means on the shield for engaging the calf's nostrils including a fixed bar attached to the shield and having an inwardly curved hook at its lower end to engage in the nostril, and a bar pivoted upon the shield and having an inwardly turned hook at its lower end, the shield being provided with openings through which the hooks extend, the opening for the hook of the pivoted bar being in the form of a slot, and detachable means for holding the bar at the inner end of said slot.
3. A calf weaner of the character described including a metallic shield having its upper

portion transversely curved to fit over the face of the animal and its lower portion extended downward and then outward, the side margins of the shield at its corners being outwardly extended, a lining of leather attached to the inner face of the shield and extended beyond the shield to form straps having adjustable engagement with each other, the shield being perforated at two adjacent points, a bar attached to the shield and having a hook extending through one of said perforations, a bar attached to the shield and having a hook extending through the other perforation and laterally adjustable therein, and straps attached to the upper corners of the shield and extending through the lining thereof and adapted to engage around the calf's neck.

In testimony whereof I hereunto affix my signature.

ROY G. SAVILLE.
